UNITED STATES PATENT OFFICE.

HERBERT H. HILLMAN, OF GRAND HAVEN, MICHIGAN.

REFRIGERATOR.

1,372,804.

Specification of Letters Patent. Patented July 16, 1918.

Application filed December 1, 1917. Serial No. 204,891.

To all whom it may concern:

Be it known that I, HERBERT H. HILLMAN, a citizen of the United States, residing at Grand Haven, in the county of Ottawa and State of Michigan, have invented new and useful Improvements in Refrigerators, of which the following is a specification.

The present invention relates to refrigerators and the like; and its object is to provide communicating chamber linings therefor which may be readily assembled, and which when assembled may be securely held together; and further, to provide such linings so assembled that there will be no leakage from their joint; and further, to provide such a lining for one chamber of the refrigerator, which lining shall have a hollow neck portion with a peripheral rib or projection, and a lining for another chamber of the refrigerator which shall have an inverted or inwardly turned hollow gradually restricted neck portion adapted to be passed over the neck portion of the first lining and to spring into contact therewith beneath the rib or projection.

These and any other objects hereinafter appearing are attained by, and the invention finds preferable embodiment in, the structure hereinafter described and illustrated in the accompanying drawings, in which:

Figure 1 is a plan view of adjacent portions of the linings for the chambers of a refrigerator, showing such linings in process of assembling;

Fig. 2 is an inside plan view of a portion of the bottom of the lining for the upper or "ice" chamber of a refrigerator;

Fig. 3 is a section of adjacent portions of said linings taken on a vertical plane corresponding with line A—A of Figs. 1 and 2, and showing said linings in process of assembling;

Fig. 4 is a like sectional view of said parts assembled, and showing portions of the refrigerator frame or casing in which the linings are contained; and

Fig. 5 shows a modified construction.

In the embodiment of the invention chosen for illustration by the drawings and for detailed description in the body of this specification, the refrigerator 1 has an ice chamber 2 and a provision chamber 3 beneath it, separated by a partition 4 having an opening 5 therethrough. A lining 6, preferably of porcelainized metal, is provided for the provision chamber and has a hollow neck por-

tion 7 extending upwardly and through the opening into the ice chamber. This neck has a projection or peripheral rib 8 extending laterally outwardly therefrom, and preferably formed by bending over a portion of said neck adjacent its mouth, as shown, prior to the porcelainizing of said lining. The ice chamber is furnished with a lining 9, preferably of galvanized iron, and having an inverted or inwardly extending hollow springable neck portion 10 the opposite sides of which converge toward the mouth 11 of said neck as shown. The linings are assembled by passing the neck portion 10 over or around the neck portion 7 and pressing it downwardly, until the edge or mouth 11 of the neck portion 10 passes beyond the projection or rib 8, whereupon the neck portion 10 springs back and its edge or mouth 11 abuts against the under edge 12 of the projection or rib 8, whereby the linings are securely held together. The beginning of the assembling operation is shown in Fig. 3, and the linings as assembled are shown in Fig. 4. It will be seen that the upwardly extending neck portion 10 of the upper lining 9 prevents water of the melting ice from leaking through the joint between the linings, such water being drained off by a suitable pipe 13, and that free air communication between the chambers is provided through the hollow neck portions.

In Fig. 5 a modified construction of the lining 6 is shown, wherein the neck portion 14 (corresponding to the neck portion 7 in the other views) is formed of separate piece from the body portion 15 of said lining and is provided with a peripheral outwardly-extending flange 16 which is secured as by spot welding to the upper wall of said body portion. A modified form of the peripheral rib surrounding the neck portion of provision chamber's lining is shown at 17.

The invention being intended to be pointed out by the claims, is not to be limited to or by details of construction shown or described.

I claim:

1. In a structure of the character described; a lining having an outwardly-extending hollow neck provided with a laterally-extending projection; and a lining having an inwardly-extending springable hollow neck whose opposite sides converge toward its mouth, and adapted to be passed over and along the first mentioned neck and

- to spring against the same beneath said projection.
2. In a structure having two chambers and a partition between them with an opening therethrough, the combination of; a lining for one chamber having a hollow neck extending through said opening and provided with a peripheral laterally-extending rib; and a lining for the other chamber having an inwardly-extending springable hollow neck whose opposite sides converge toward its mouth, and adapted to be passed over and along the first mentioned neck and to spring against the same beneath said rib.
- 5 3. In a structure having two chambers and a partition between them with an opening therethrough, the combination of; a lining for one chamber having a hollow neck extending through said opening and pro-
- 10 vided with a peripheral laterally-extending rib formed by bending over a portion of said neck adjacent its mouth; and a lining for the other chamber having an inwardly-extending springable hollow neck whose op-
- posite sides converge toward its mouth, and 25 adapted to be passed over and along the first mentioned neck and to spring against the same beneath said rib.
4. In a structure of the character described; a lining having an outwardly-extending hollow neck provided with a laterally-extending projection; and a lining having an inwardly-extending springable hollow neck whose opposite sides converge toward its mouth, and adapted to be passed 30 over and along the first mentioned neck and to spring against the same beneath said projection; the first-mentioned neck being formed of separate piece from the first-mentioned lining and being provided with an 35 outwardly-extending flange securely joined to the first-mentioned lining and surrounding an orifice therethrough.

In testimony whereof I have hereunto set my hand at Grand Rapids, Michigan, this 28th day of November, 1917.

HERBERT H. HILLMAN.
